(57) **CLAIM**

I claim the ornamental design for a slatwall for wall mounting devices, as shown and described.

DESCRIPTION

FIG. 1 is a top, front, left side, perspective view of a slatwall for wall mounting devices.

FIG. 2 is a right side elevation view of the slatwall for wall mounting devices of FIG. 1, the left side being a mirror image. FIG. 3 is a front elevation view of the slatwall for wall mounting devices of FIG. 1.

FIG. 4 is a rear elevation view of the slatwall for wall mounting devices of FIG. 1.

FIG. 5 is a top plan view of the slatwall for wall mounting devices of FIG. 1.

FIG. 6 is a bottom plan view of the slatwall for wall mounting devices of FIG. 1.

FIG. 7 is a top, front, left side, perspective view of another embodiment of a slatwall for wall mounting devices.

FIG. 8 is a right side elevation view of the slatwall for wall mounting devices of FIG. 7, the left side being a mirror image of the slatwall for wall mounting devices of FIG. 1.

FIG. 9 is a front elevation view of the slatwall for wall mounting devices of FIG. 7.

FIG. 10 is a rear elevation view of the slatwall for wall mounting devices of FIG. 7.

FIG. 11 is a top plan view of the slatwall for wall mounting devices of FIG. 7; and,

FIG. 12 is a bottom plan view of the slatwall for wall mounting devices of FIG. 7.

The dominant features of my design reside in multiple T-slots extending along the length of the slatwall for wall mounting devices and spaced apart, in combination with an angled slot extending along the top edge, back side, of the slatwall for wall mounting devices and an angled slot extending along the bottom edge, front side, of the slat wall.

1 Claim, 5 Drawing Sheets
